UNITED STATES PATENT OFFICE

LINDSAY THORNE CRABBE, OF CHICAGO, ILLINOIS, ASSIGNOR TO PHOENIX METAL CAP CO., INC., OF CHICAGO, ILLINOIS, A CORPORATION OF NEW YORK

JAR CLOSURE

Application filed August 7, 1930. Serial No. 473,652.

The invention relates to new and useful improvements in closures for tumblers or the like, and more particularly to a closure which can be easily detached from the tumbler.

5 An object of the invention is to provide a closure for a tumbler having a projecting shoulder in its outer wall adjacent the upper edge thereof, which closure may be secured in tight sealing contact with the tumbler by 10 a bending of the depending skirt or flange inwardly beneath the shoulder.

A further object of the invention is to provide a closure for a tumbler of the above type, wherein the depending skirt is a part 15 of a holding band having a locking tongue securing the ends thereof together.

Other objects and advantages of the invention will appear hereinafter.

Referring to the accompanying drawing, 20 Fig. 1 is a view in elevation of a tumbler or jar sealed with a cap embodying the present invention;

Fig. 2 is a fragmentary view, on an enlarged scale and partly in section, illustrating 25 the cap placed in sealing position and before being fastened in place on the container;

Fig. 3 is a similar view of the same cap after being fastened in sealing position.

The invention is directed to a closure for 30 tumblers or the like. A tumbler is shown in the drawing at 11, and this tumbler is provided with a projecting portion 12 forming a shoulder located in the outer wall of the tumbler and adjacent its upper end. The 35 closure for sealing the tumbler includes a sealing cap or disk 14 provided on its under face with a sealing composition 15 adapted to contact with the upper edge of the wall of the tumbler. The disk or cap 14 is secured 40 in sealing contact with the tumbler by a fastening band 17. The band 17 has an inwardly extending portion 18 which overlies and engages the outer face of the disk or cap 14. The band has a vertically extending 45 skirt or flange, and the lower edge of the skirt is formed with a bead 19. The ends of the band 17 are secured together by a fastening lug 21 formed in one end of the band and passing through a slot in the extending 50 tongue 22 of the other end of the band. Thus

the ends of the band are firmly secured together. The cap formed, as stated above, is applied to the tumbler, and the sealing composition 15 brought into engagement with the end of the wall of the tumbler. The closure 55 is forced downwardly, making a tight sealing contact between the cap or disk 14 and the tumbler, and while so held, the skirt or flange of the band 17 is provided with an inwardly extending annular bead 24. This annular bead is formed in the skirt above the 60 outwardly projecting bead 19, and so as to extend beneath the shoulder 12 on the tumbler. The forming of the bead 24 in the skirt locks the closure to the tumbler, holding the 65 disk firmly clamped against the end of the tumbler wall, and thus insuring a permanent hermetic seal between the disk and the tumbler, due to the sealing composition being firmly pressed against the parts. The 70 disk 14 is preferably provided with an annular bead disposed within the inner wall of the tumbler, and this forms a pocket for the sealing material which confines the sealing material so as to aid in the producing of a 75 tight seal. The bead 24 formed in the skirt is uniformly formed all the way around the skirt, and across and in the lug 21 and tongue 22. This insures that the ends of the band where they are joined will be tightly held 80 from movement in a vertical direction, inasmuch as the metal forming these parts is forced underneath the ledge on the tumbler. By the construction described, the closure will be very firmly attached to the tumbler, 85 and yet it can be readily removed by lifting the tongue 22 and breaking the lug connection between the ends of the band. The bead 19 at the lower end of the skirt strengthens the 90 skirt and aids in holding the shape of the formed bead 24, so that the closure is very tightly secured to the tumbler.

What is claimed is:

The combination of a tumbler having an outwardly projecting portion adjacent its 95 upper end, a closure for said tumbler comprising a sealing disk, a sealing composition between the disk and the end of the tumbler wall, and a securing band overlying said sealing disk and provided with a depending 100

skirt extending along the outer face of the tumbler, one end of said band having a releasing tongue and the other end having a locking lug passing through the tongue for joining the ends of the band, said skirt at the lower edge thereof having an outwardly projecting bead, and an annular inwardly projecting securing bead of uniform cross section extending all the way around said skirt and across said tongue and lug and bearing against said projection for holding the closure in tight sealing contact with the tumbler.

In testimony whereof, I affix my signature.
LINDSAY THORNE CRABBE.
